UNITED STATES PATENT OFFICE.

DOCTOR FRANKLIN OLIVER, OF OAKLAND, CALIFORNIA; LILLIE F. OLIVER EXECUTRIX
OF SAID D. FRANKLIN OLIVER, DECEASED.

DOOR-BUFFER.

1,262,551.

Specification of Letters Patent.

Patented Apr. 9, 1918.

Application filed July 7, 1911, Serial No. 637,278. Renewed August 18, 1917. Serial No. 186,928.

To all whom it may concern:

Be it known that I, Doctor FRANKLIN OLIVER, a citizen of the United States, and a resident of Oakland, in the county of Alameda and State of California, have invented 5 a new and Improved Door-Buffer, of which the following is a full, clear, and exact description.

The object of the invention is to provide 10 a new and improved door buffer, arranged not to interrupt the door on the latter closing easily, but on the door moving shut with more than ordinary force or speed, to interrupt the closing movement of the door 15 and to cushion it without damage to the door, the buffer door casing and other connected parts.

For the purpose mentioned, use is made 20 of a cushioning device and an actuating member for the said cushioning device, the said actuating member operating freely without affecting the cushioning device on the door closing with ordinary force, and the said actuating member rendering the 25 cushioning device active on being struck with force on the door closing with more than ordinary force.

A practical embodiment of the invention is represented in the accompanying drawings 30 forming a part of this specification, in which similar characters of reference indicate corresponding parts in all the views.

Figure 1 is a perspective view of the door buffer as applied to a door casing; 35

Fig. 2 is a side elevation of the door buffer in position on the door casing, the latter being shown in section and part of the buffer broken out;

Fig. 3 is a sectional side elevation of the 40 same on the line 3—3 of Fig. 4;

Fig. 4 is a sectional plan view of the same on the line 4—4 of Fig. 3;

Fig. 5 is a side elevation of a modified 45 form of the improvement and its position on the door casing, the latter being shown in section;

Fig. 6 is a sectional side elevation of the 50 same;

Fig. 7 is a face view of the same; and

Fig. 8 is a sectional plan view of the same on the line 8—8 of Fig. 5.

The door buffer is mounted on a suitably

constructed support, preferably formed of a plate A, preferably attached to the side of the door casing B opposite the one carrying the hinges for the door, the said plate A being fastened in place by screws C and being provided at the inner face with brackets A', A² extending into a recess B' formed in the door casing A adjacent to the stop bead B² for the door. The plate A is provided with an angular extension A³ extending on the front face of the stop bead B², and the said plate A and its extension A³ is provided with an opening A⁴ through 65 which projects the free end of a lever D fulcrumed loosely on a tubular cam E engaging a tubular cam F mounted to slide up and down on the polygonal portion G' on a bolt G held on the lower bracket A² and 70 having a threaded portion G², on which screws a nut G³ having a bearing in the upper bracket A'. The sliding cam F is pressed on on top by the lower end of a spring H coiled on the bolt G and abutting 75 at its upper end against the under side of the nut G³, so that when the latter is turned on the threaded portion G² the tension of the spring H can be increased or diminished according to the direction in 80 which the nut G³ is turned. In order to gain convenient access to the nut G³ for the purpose of turning the same, the plate A is provided with an opening A⁵ for the insertion of a suitable tool to engage vertical 85 grooves G⁴ formed in the peripheral face of the nut G³ to turn the latter.

The cam F is preferably provided with spiral ribs engaging spiral grooves in the cam E so that when the cam E is turned in 90 the direction of the arrow a' then the cam F is caused to slide upward on the polygonal portion G' of the bolt G and against the tension of the heavy spring H, and when the cam E is released the tension of the 95 spring H forces the cam F downward and in doing so the cam F turns the cam E back to normal position.

The bottom of the sliding cam G is normally seated on a washer I held against 100 movement on the polygonal portion G' of the bolt G, the washer resting on the bracket A², and a ball or other bearing J being interposed between the rotatable cam E and

the washer I, as plainly indicated in Fig. 3. A spring K is coiled around the washer I and has one end secured to the bracket A² while the other end is attached to the lever 5 D so as to normally hold the latter in a forward position as indicated in the drawings. The free or projecting end of the lever D is preferably in the shape of a fork, between the members of which is 10 mounted a pawl L on a vertical pivot L' attached to the fork. The forward end of the pawl L projects slightly beyond the forward end of the lever D while the rear end of the pawl L is provided with ratchet 15 teeth L² adapted to engage ratchet teeth E' formed on the peripheral face of the outer turnable cam E. A spring L³ is attached to the forward end of the pawl L and rests with its free end on the lever D so as to 20 normally hold the pawl L in such a position that its ratchet teeth L² are out of engagement with the ratchet teeth E'. The end of the pawl L is provided with an extension L⁴ engaging a projection D' formed 25 on the lever D to limit the outward swinging movement of the rear end of the pawl L.

As previously mentioned, the spring K holds the lever D and its pawl L in a forward position, as shown in Figs. 1, 2, 3 and 4, and the spring L³ holds the pawl L out of engagement with the turnable cam E, and consequently the lever D is free to swing on the cam E as a fulcrum and only against 30 the tension of the light spring K. Now when the door is closed with ordinary force or speed the free end of the door finally strikes the forward end of the pawl L, but as the impact is very slight the pawl is not 35 caused to turn but a swinging motion is given to the lever D against the tension of the spring K so that the door closes easily. When the door, however, is slammed or closed with more than ordinary force or 40 speed then the impact of the door on the pawl L is such as to swing the same on its pivot L' whereby the teeth L² are moved in engagement with the ratchet teeth E' so that the impact is transmitted to the lever 45 D and to the cam E to rotate the latter, whereby the cam F is forced to slide upward on the polygonal portion G' of the bolt G against the tension of the spring H. Thus by the arrangement described the cushioning 50 device is brought into action to cushion the door in case the latter is slammed with more than ordinary force, but when the door is closed with ordinary force or speed the cushioning device is not actuated and 55 remains dormant as the lever D then swings freely on the cam E and against the tension of the light spring K.

When the force of the slammed door has been spent in turning the lever D in the di-

rection of the arrow a' and with it the cam 65 E to raise the cam F against the tension of the spring H then the latter returns the parts to normal position, and then the spring L³ throws the pawl L out of engagement with the ratchet teeth E' to allow the 70 lever D to swing freely in the direction of the arrow a' so that the door can move shut against the tension of the light spring K. It is understood that the free end of the 75 lever D and the pawl L can readily pass through the opening A⁴ into the recess B' in the door casing B. When the door strikes the forward end of the pawl L and imparts a swinging motion to the same then the 80 face of the forward end of the pawl L comes approximately flush with the forward end of the lever D so that the door bears against both the pawl L and the lever D to swing the latter in the direction of the arrow a' (see Fig. 4).

In the modified form shown in Figs. 5, 6, 7 and 8, the supporting plate N is attached by screws N' to the casing O, and the plate is provided with an inwardly-extending bracket N² passing into a recess O' formed 90 in the door casing O. On the bracket N² is held a vertically-disposed bolt P fastened in place by a set screw P' screwing in the plate N and the bracket N², and the said bolt P is provided with a lengthwise-extending groove P², into which extends the inner end Q' of a helical spring Q fastened at its outer end to a disk R, on which is mounted to swing loosely a lever S carrying a pawl T provided with ratchet teeth 100 T' adapted to engage ratchet teeth R' on the peripheral surface of the disk R. The pawl T is provided with slots T', T², through which pass pins S², S³ forming part of the lever S and against the pin S² presses a spring T² held in the pawl T and abutting against a set screw T⁴ screwing in the forward or base end of the pawl T. The spring T² serves to normally hold the pawl T in 105 an outermost position with its teeth T' out of engagement with the teeth R' on the disk R. The disk R is provided at the bottom and top with beveled annular surfaces R², R³, of which the lower or bottom surface R² engages a correspondingly shaped beveled surface N³ on the bracket N², and the beveled surface R³ is in engagement with a correspondingly shaped surface U' formed 110 on a disk U having a tongue U² extending into the groove P² so as to hold the disk U 115 against turning on the bolt P, to allow the disk U to slide up and down on the bolt P. A spring V bears with its lower end on the disk U and abuts with its upper end against the under surface of nut P³ screwing on the 120 upper threaded end of the bolt P. The nut P³ as well as the head P⁴ of the bolt P are provided with vertical slots for engagement 125

by tools inserted through openings N^4 , N^5 formed in the plate N to permit of turning the nut P^3 while holding the bolt P stationary to adjust the tension of the spring 5 V . A light spring W is fastened at one end to the peripheral face of the disk R while the other end of the spring W is attached to a pin S^4 forming part of the lever S , which latter is preferably made of two 10 parts connected with each other by the pins S^2 , S^3 and S^4 . The spring W serves to normally hold the lever S in a forward position so that the free end of the lever S as well as the forward end of the pawl T 15 project into the path of the door X to be checked and cushioned. A stop pin R^4 is attached to the disk R and abuts against the forward wall of an opening N^6 formed in the plate N and through which opening 20 extends the lever S and its pawl T .

When the door is closed with ordinary force or speed and it strikes the pawl T then the latter's position is not changed relative to the lever S , and consequently a rearward 25 swinging motion is given to the lever S on which the pawl T is held as above described, the lever S swinging in the direction of the arrow b' against the tension of the light spring W . When the door, however, is 30 slammed and strikes the pawl T with considerable force then the spring T^3 is compressed and the pawl is caused to move on the lever S to engage the ratchet teeth T' with the ratchet teeth R' of the disk R , 35 whereby the latter is turned with the lever S in the direction of the arrow b' . On turning the disk R the helical spring Q is placed under tension so as to cushion or check the door and when the force of the slamming 40 of the door is spent the spring Q returns the disk R , the lever S and pawl T by turning the said parts in the inverse direction of the arrow b' , and as the force of the door against the pawl T is also spent the spring 45 T^3 returns the pawl T to normal position, that is, moves the ratchet teeth T' out of engagement with the ratchet teeth R' so that the lever S is unlocked and is free to swing independent of the cushioning device and 50 against the tension of its light spring W . The door X can now be pulled shut, it being understood that in doing so the lever S is swung inwardly in the direction of the arrow b' completely free of the cushioning 55 device, which remains dormant for the time being.

In order to prevent an easy turning of the disk R in addition to the force exerted by the spring Q , use is made of the friction disk U and the spring V to hold the disk R against easy turning, it being understood that both surfaces R^2 , R^3 are in contact with the fixed surfaces N^3 , U' of the bracket N^2 and the disk U , respectively,

and of which the disk U is pressed downwardly by the action of the spring V , the tension of which can be adjusted by the nut P^3 as previously explained.

Having thus described my invention, I claim as new and desire to secure by Letters Patent:—

1. A door buffer, comprising a cushioning device, an actuating member for the cushioning device, and means controlled by the actuating member whereby to render the cushioning device inactive on the door closing with the ordinary force and active on the door closing with more than ordinary force.

2. A door buffer, comprising a cushioning device, an oscillating member, and means for actuating the said cushioning device from the said member on slamming the door, the said oscillating member oscillating free of the said cushioning device on closing the door with ordinary force.

3. A door buffer, comprising a cushioning device, concealed in the door casing, and an oscillating actuating member extending into the path of the door to move with the latter on closing the door with ordinary force and without affecting the said cushioning device, the said actuating member engaging the cushioning device on being struck with force by the said door on the latter being slammed.

4. A door buffer, comprising a cushioning device under heavy spring pressure, a lever under light spring pressure and adapted to be oscillated on the door closing, and a spring pawl and ratchet connection between the said lever and the said cushioning device and inactive on closing the door with ordinary force to allow the lever to swing freely with the door, the said connection becoming active on closing the door with more than ordinary force to connect the lever with the said cushioning device.

5. A door buffer, comprising a cushioning member under heavy spring pressure and having ratchet teeth, a lever mounted to normally swing freely relative to the said cushioning member, and a spring-pressed pawl mounted on the said lever and adapted to engage the said ratchet teeth, the pawl being normally out of engagement with the said ratchet teeth and in the path of the door, and adapted when struck by said door with ordinary force to remain out of engagement with said ratchet teeth allowing the lever to turn freely, said pawl being also adapted when struck by the door with more than ordinary force, to engage the ratchet teeth on the cushioning member and turn the latter against the heavy spring pressure to cushion the door.

6. A door buffer, comprising an outer cam and an inner cam mounted to slide axially

by the action of the said outer cam, a heavy spring bearing on the said inner cam, ratchet teeth on the outer cam, a lever mounted to oscillate on the said outer cam, 5 and a spring-pressed pawl on the lever and adapted to engage the said ratchet teeth to actuate the outer cam.

7. A door buffer, comprising an outer cam and an inner cam mounted to slide axially 10 by the action of the outer cam, a heavy spring bearing on the said inner cam, ratchet teeth on the outer cam, a lever mounted to oscillate on the said outer cam, a spring-pressed pawl on the lever and adapted to 15 engage the said ratchet teeth, and a light spring pressing the said lever.

8. A door buffer, comprising an outer cam and an inner cam mounted to slide axially by the action of the said outer cam, 20 a heavy spring bearing on the said inner cam, ratchet teeth on the outer cam, a lever mounted to oscillate on the said outer cam, a spring-pressed pawl on the lever and adapted to 25 engage the said ratchet teeth to actuate said outer cam, and means for adjusting the tension of the said heavy spring.

9. A door buffer, comprising a support for attachment to the door casing, a bolt held on the said support and provided with a 30 polygonal portion on the shank, a sliding cam mounted to slide on the said polygonal bolt portion, an actuating cam mounted to turn on the sliding cam for imparting sliding motion to the same, the said actuating 35 cam having exterior ratchet teeth, a lever fulcrumed loosely on the said actuating cam, a spring-pressed pawl on the said lever and adapted to engage the said ratchet teeth to actuate said actuating cam, a heavy spring 40 coiled on the said bolt and bearing on the said sliding cam and against the nut of the bolt, and a light spring pressing the said lever.

10. A door buffer, comprising a support 45 for attachment to the door casing, a bolt held on the said support and provided with a polygonal portion on the shank, a sliding cam mounted to slide on the said polygonal bolt portion, an actuating cam mounted to 50 turn on the sliding cam for imparting sliding motion to the same, the said actuating cam having exterior ratchet teeth, a lever fulcrumed loosely on the said actuating cam, a spring pressed pawl on the said lever and 55 adapted to engage the said ratchet teeth, a heavy spring coiled on the said bolt and

bearing on the said sliding cam and against the nut of the bolt, a nut on the bolt for adjusting the tension of the said spring, a light spring pressing the said lever, and a 60 bearing for the bottom of the said actuating cam to turn on.

11. A door buffer, comprising a light resistance device actuated upon the application of ordinary force, and a heavy resistance device controlled by the light resistance device and actuated thereby upon the application of more than ordinary force. 65

12. A door buffer, comprising a light resistance device actuated on closing the door, 70 a heavy resistance device, and a connection member moving bodily with the said light resistance device and normally out of engagement with the said heavy resistance device, the said connecting member moving 75 into engagement with the said heavy resistance device on forcibly actuating the light resistance device when slamming the door.

13. A door buffer, comprising resistance devices, one being provided with a light 80 spring and the other with a heavy spring, and a connecting member carried by the said light spring resistance device and out of engagement with the said heavy spring resistance device on gently closing the door, 85 the said connecting member moving into engagement with the said heavy spring resistance device on forcibly actuating the said light spring resistance device when slamming the door. 90

14. In a door buffer the combination of a light resistance device, and a heavy resistance device with which the light resistance device is engageable when the latter is subjected to more than ordinary force. 95

15. A door buffer comprising a cushioning member, an actuating member therefor and passively coupled thereto, and means controlled by the actuating member to render the cushioning member inactive on the door 100 closing with ordinary force, and actively coupling the actuating and cushioning members upon the door members upon the door closing with more than ordinary force.

In testimony whereof I have signed my 105 name to this specification in the presence of two subscribing witnesses.

DOCTOR FRANKLIN OLIVER.
